CLAIM

The ornamental design for a padded snow and ice guard for a vehicle windshield or rear window, as shown and described.

DESCRIPTION

FIG. 1 is a front elevational view of a padded snow and ice guard for a vehicle windshield or rear window showing my new design;

FIG. 2 is a rear elevational view; and,

FIG. 3 is a top plan view thereof on a reduced scale rotated ninety degrees with respect to FIGS. 1 and 2.

FIG. 3

FIG. 1

FIG. 2
